UNITED STATES PATENT OFFICE.

EMIL S. LARSON, OF STANTON, AND FRANK L. DINSMORE, OF PRESCOTT, IOWA.

TYPEWRITER KEYBOARD.

Application filed January 27, 1927. Serial No. 164,066.

This invention relates to the class of typewriters and pertains particularly to a key board construction.

The primary object of this invention is to provide, in a manner as hereinafter set forth, a typewriter keyboard in which the keys are divided into two groups, one group being controlled by the right hand and the other group by the left hand, each row of keys of each group being inclined upwardly from one side of the machine to the central portion thereof thus so positioning the keys to conform to the natural position assumed by the hands when extended to position over the board.

As is of course well known, typewriters at present in use have all of the keys of each row arranged in the same plane and when placing the hands in position to type it is necessary to twist the wrists and forearms in order to bring the hands to proper position. This produces a muscular strain which is often times very pronounced, particularly with the beginner.

A further object of this invention is to produce a key board having the foregoing advantageous features, which will entail no greater expense in construction than key boards of the present type.

Numerous other objects and advantages of this invention will become apparent as the description of the same proceeds and the invention will be best understood from a consideration of the following detailed description taken in connection with the accompanying drawings taken in connection with this specification, with the understanding however, that the invention is not confined to any strict conformity with the showing of the drawings but may be changed or modified so long as such changes or modifications mark no material departure from the salient features of the invention as expressed in the appended claims.

In the drawings:

Figure 1 shows a typewriter in front elevation, equipped with the key board of the character embodying this invention.

Figure 2 is a plan view of the key board and a portion of the front of the typewriter.

Figure 3 is a side elevational view of the key board and the front portion of the typewriter.

Figure 4 is a front elevational view of the slotted key bar guide plate.

Figure 5 is a detailed perspective view of a key and the bar associated therewith.

Referring now to the drawings in detail wherein like numerals of reference indicate corresponding parts throughout the several views, numeral 1 indicates generally a typewriter of conventional design having the usual key-board frame 2 projecting forwardly thereof, within which frame the type operating keys are arranged.

In the key-board construction of the character embodying this invention, forty-one of the forty-two type operating keys are divided into two groups, a right hand group of twenty-one keys, indicated by the numeral 3, and a left hand group of twenty keys indicated by the numeral 4, the forty-second key of the board standing alone as will be herein-after described. This lone key is indicated by the numeral 5 and as shown is the "Y" key, which key occupies substantially the central position of the key-board group.

Referring to Figure 5, a single key-button and supporting bar is shown, which may represent one of the right or left hand group of keys. For the present description it will be assumed that this is one of the right hand group of keys 3 and will be labeled accordingly.

Each of these keys comprises the upstanding portion 6 which merges at its lower end with a right-angularly related portion 7, the rear end of which portion 7 is connected to the elongated bar 8 by the intermediate portion 9. When the key is in position in the typewriter the bar 8 extends horizontally from the front to the rear thereof and is connected to a type carrying arm (not shown) by the link member 10, the lower portion of which link member is pivotally connected to the bar 8 through the medium of the lug 11. Under normal conditions, that is in the ordinary typewriter, the portion 6 which supports the key would be arranged in vertical position, however, in the present key-board construction the portion 9 is slightly bent to one side thus causing the portion 6 to be inclined to the right of the key-board. From this it will be readily understood that all of the keys 3 which compose the right hand group will be inclined in the same direction and the up-

right portion 6 of the keys of each row are of gradually increasing length from the outer to the inner end of the row thus causing the group to gradually decrease in height from 5 the inner to the outer portion thereof.

The keys 4 which make up the left hand group have the upstanding portions thereof which correspond to the portion 6 of the key and bar structure shown in Figure 5, inclined 10 to the left, thus arranging this group of keys with the surfaces thereof sloping downwardly from the inner to the outer side of the keyboard.

The "Y" key 5 is arranged vertically between 15 the right and left hand groups and thus in a manner stands apart from these groups.

The key bar guide board is indicated by the numeral 12 the lower edge of which board has cut thereinto a plurality of slots. These 20 slots are arranged in two groups, one group extending from one end of the board to a point adjacent the center thereof as indicated by the numeral 13, the slots of this group being inclined to the left or adjacent end of the board. The other group of slots is indicated by the numeral 14 and these slots are inclined 25 to the right as shown and a single vertical slot 15 is formed at substantially the central portion of the board.

It will be readily understood that the group 30 of slots 13 which are inclined to the left are designed to receive and guide the outer portions of the key bars of the right hand group while the slots 14 are designed to receive and 35 guide the key bars of the left hand group, and the central slot 15 receives the bar of the central key 5.

From the foregoing description, it will be 40 readily understood how by forming the keys into two groups or banks which gradually increase in height to the central portion of the keyboard, the strain incident to the use of a flat key board is overcome.

Having thus described our invention, what 45 we claim is:

1. A typewriter key-board having the keys of each transverse row of gradually increasing height from each end to the central portion of the row and having those keys upon

each side of the transverse center of the board 50 inclined toward the adjacent side of the board, and means to guide said keys upon actuation in planes perpendicular to the planes of the inclination of the rows.

2. A typewriter key-board of the character 55 described transversely divided substantially centrally thereof to arrange the keys in two main groups, excluding one key, the keys of each group being of gradually increasing height from the outer to the inner side thereof and inclined toward the adjacent outer side, said excluded key being positioned vertically substantially centrally of the key-board, and a key bar guide plate having a plurality of slots formed in the lower edge of 60 the same for the reception of the key bars, said slots being arranged in two groups corresponding to said key groups, and a central vertical slot to receive the bar of the centrally positioned key.

3. A typewriter key board wherein the 65 keys are divided into two groups arranged on opposite sides of the transverse center of the key board and a single central key positioned between said groups, each row of keys of 70 each group running longitudinally of the key board being of gradually decreasing height from the inner to the outer side of the group, and means to guide said keys upon actuation in planes perpendicular to the planes of inclination of the rows.

4. A type writer key board of the character described, including key bars, each terminating in the forward end in an upwardly extending portion, wherein the keys are divided 75 into two groups arranged on opposite sides of the transverse center of the board and a single central key positioned between said groups, each of the key bars of each group having the upwardly extending portion thereof inclined away from the transverse center of the key board, and means to support the key bars to cause movement of keys in planes perpendicular to the key edge.

In testimony whereof we affix our signatures,

EMIL S. LARSON.
FRANK L. DINSMORE.
